UNITED STATES PATENT OFFICE.

WILLIAM RUSSELL FREE, OF PIQUA, OHIO.

GRAMOPHONE-AMPLIFIER.

1,318,201.

Specification of Letters Patent.

Patented Oct. 7, 1919.

Application filed August 28, 1918. Serial No. 251,788.

To all whom it may concern:

Be it known that I, WILLIAM RUSSELL FREE, a citizen of the United States, residing at Piqua, in the county of Miami and State of Ohio, have invented certain new and useful Improvements in Gramophone-Amplifiers, of which the following is a specification.

This invention relates to the class of 10 acoustics and more particularly to sound boxes or transmitting devices for gramophones and graphophones.

The invention has for its object the provision of an amplifier adapted to be positioned within the sound box or horn of a graphophone so as to produce a clearer and louder sound, and for this purpose, I provide in a novel relation, a transmitter and a receiver associated in an electrical circuit in 20 connection with a generator or dynamo driven by the motor of the machine and having coupled in the circuit, a resistance element to regulate the tone as desired, while the sound produced is received by the transmitter and conveyed by the receiver as and 25 for the purposes specified.

With the above and other objects in view, as will appear as the description proceeds, the invention comprises the novel features of 30 construction, combination of elements and arrangement of parts which will be more fully described in the following specification and then finally embodied in the clauses of the claim appended hereto.

Reference is had to the accompanying drawings forming a part of this application, in which—

Figure 1 is a perspective view partly in section of a gramophone equipped with my 40 improved tone and sound amplifier,

Fig. 2 is an enlarged sectional view showing the amplifier device,

Fig. 3 is a diagrammatic view showing the circuit arrangement, also the connection between the generator or dynamo and the 45 motor of the machine,

Fig. 4 is a plan view of the resistance switch, and

Fig. 5 is a sectional view of the top of the 50 gramophone and switch applied thereto.

Referring to the drawings in detail, the numeral 10 designates the cabinet of a graphophone or gramophone having the usual cover 11 designed to close over the table 12 55 adapted to be rotated by the usual motor contained within a compartment or chamber

13 so as to revolve the disk record 14 therewith. The tone arm is designated at 15 having the gramophone sound box 16 with a needle 17 co-operating with the record, said 60 tone arm leading to the sound box or horn 18 which issues from the cabinet, which latter may be of any preferred type, adapted to contain records if desired, or not. The motor may be of any suitable type, and may 65 be electrically driven or a spring motor adapted to be wound by a crank 19 so as to rotate the table 12 when the brake 20 is released, as it is thought will be understood.

In order to amplify the tone and sound issuing from the tone arm and the sound box or horn 18, I interpose in the reduced portion 21 of the sound box or horn, a casing 22 designed to contain a transmitter 23 with a carbon grain sensitive microphone, the same 70 being coupled to the reduced portion 21, by the tubular connection at 24. A partition 25 is provided in the casing 22 and the casing is thereby divided into a pair of chambers in the other of which is disposed a receiver 26, the receiver being of the loud talking 75 type and electromagnetic, while the transmitter has a microphone of the sensitive type. The receiver has a connection with the sound box or horn 18 and the terminals 80 27 and 28 of the transmitter and receiver respectively are connected by a conductor 29 extending through the partition 25. The other terminals 30 and 31 of the transmitter and the receiver respectively, are connected 85 through the medium of conductors 32 and 33 with a generator or dynamo 34 operatively connected to the motor 13 through the medium of a shaft 35 or other operative connections, by which the dynamo may be rotated at the proper speed, by means of the 90 motor which turns the table for revolving the disk record. Interposed in the circuit is a switch rheostat 36, consisting of a variable 95 resistance in the form of a plurality of contacts 37, one end of the generator being connected to the movable contact member 38 of the switch rheostat by a conductor 39, while the conductor 32 is connected to one of the transmitter leads and to one of the contacts 100 38 of the switch rheostat and a conductor 40 from the conductor 33 leads to the other extreme contact of the switch rheostat. The contact 38 is mounted on a pivot 41 designed to be passed through the top of the cabinet 10 110 10 and operated through the medium of a handle portion 42 provided with an index

pointer 43 coöperating with a circular scale plate 44, which latter indicates the degrees of resistance, which shall be such as to produce the proper tone and clarify the same 5 according to the desires of the person operating the machine. It is of course understood that the sound is received by the transmitter and conveyed through the circuit wires to the receiver, from which it is transmitted 10 into the horn or sound box 18 in the proper tones desired according to the regulation of the movable contact 38 of the switch rheostat, the current being generated by driving the generator or dynamo 34 through the 15 instrumentality of the motor operating the machine. It is of course understood that the motor may be of any preferred type, such as spring motor or electrically operated motor of usual construction and in view of 20 the particular type of transmitter and receiver employed, the sound will be considerably amplified, thereby producing a clear tone as well as a louder tone.

From the foregoing description taken in 25 connection with the accompanying drawings, it is thought that a clear and comprehensive understanding of the construction, operation and advantages of my invention may be had, and while I have shown 30 and described the device as embodying a specific structure, I desire that it be understood that such changes may be made in said structure as do not depart from the spirit and scope of the invention as claimed. 35 Having thus described my invention, what I claim as new, and desire to secure by Letters Patent, is:

1. The combination with a graphophone having a sound box and a motor for driving 40 the record receiving table for engagement by the sound box carried by the tone arm in the usual manner, a casing interposed in the tone arm, a transmitter therein having connection with the tone arm, a receiver having 45 electrical connection with the transmitter and leading to the horn or sound box, a dynamo operatively connected with the motor of the machine, and connected in an electrical circuit with the transmitter and re-

ceiver, and a rheostatic switch interposed in 50 the circuit between the generator and the receiver and transmitter whereby to vary the resistance in said circuit.

2. The combination with a graphophone, 55 of a casing interposed between the tone arm and the horn thereof, a partition in said casing, a transmitter in said casing between the tone arm and the partition, said transmitter having a carbon grain sensitive microphone, a receiver disposed between the partition in the casing and the horn, said receiver having a loud talking electromagnetic microphone, a conductor connecting two terminals of the transmitter and receiver, a 60 source of electrical energy having electrical connection with the receiver and with the transmitter, and an adjustable resistance element in the connection between the source of electrical current and the receiver and transmitter.

3. The combination with a graphophone, 65 of a casing interposed between the tone arm and the horn thereof, a partition in said casing, a transmitter in said casing between the tone arm and the partition, said transmitter having a carbon grain sensitive microphone, a receiver disposed between the partition in the casing and the horn, said receiver having a loud talking electromagnetic microphone, a conductor connecting two 70 terminals of the transmitter and receiver, a source of electrical energy having electrical connection with the receiver and with the transmitter, and an adjustable resistance element in the connection between the source 75 of electrical current and the receiver and transmitter for varying the current flowing through said transmitter and receiver, said resistance element including a series of contacts associated with a resistance coil, and a 80 movable contact coöperating with said first mentioned contact, and an index plate under which said movable contact is operable to vary the degrees of resistance.

In testimony whereof, I affix my signature 85 hereto.

WILLIAM RUSSELL FREE.
